UNITED STATES PATENT OFFICE.

FRANK R. McBERTY, OF NEW ROCHELLE, NEW YORK, ASSIGNOR TO WESTERN ELECTRIC COMPANY, OF NEW YORK, N. Y., A CORPORATION OF ILLINOIS.

TELEPHONE-TRANSMITTER.

1,102,600.

Specification of Letters Patent.

Patented July 7, 1914.

Application filed March 1, 1911. Serial No. 611,631.

To all whom it may concern:

Be it known that I, FRANK R. McBERTY, citizen of the United States, residing at New Rochelle, in the county of Westchester and State of New York, have invented a certain new and useful Improvement in Telephone-Transmitters, of which the following is a full, clear, concise, and exact description.

10 This invention relates to telephone transmitters and its object is to improve the transmitting qualities of such instruments.

Transmitters are to a certain extent limited in strength and quality of transmission 15 by the maximum current which they can safely withstand. The current manifests itself by heat generated in the carbon granules and in the electrodes, resulting when the current is too strong, in what is known 20 as "burning." The greatest amount of heat is retained in the granules at the central part of the carbon chamber.

This invention provides improved means 25 for rapidly dissipating the heat generated within the carbon chamber, thereby permitting a heavy current to be used, resulting in very loud and clear transmission without "burning."

In accordance with the invention there is 30 provided a comparatively large block of good heat conducting material surrounding the carbon chamber. Preferably this block forms the side walls of the chamber and is in direct contact with the carbon granules.

35 The invention furthermore provides means, preferably in the form of spurs extending from the surrounding mass of conducting material to points within and near the central part of the carbon chamber. 40 These projections may be formed integrally with the surrounding mass and are generally of conical formation.

The invention will be more fully understood by reference to the accompanying 45 drawing, wherein—

Figure 1 is a rear elevation, with the casing removed, of a telephone transmitter embodying the invention; Fig. 2 is a side elevation thereof in section along the line 2—2 50 of Fig. 1, except that the transmitter elements within the casing are shown in full lines; Fig. 3 is an enlarged detail front view and Fig. 4 an enlarged detail sectional view of the transmitter.

55 In the drawing the transmitter elements

are shown inclosed within a casing 1 and a face plate 2 to which is attached the usual mouth-piece 3. A diaphragm is supported upon the face plate and insulated therefrom by a rubber band 5 stretched on its edge, the 60 diaphragm being held in place by a ring 6 which bears against its edge by pressure of screws 7 engaging arms 8 of the ring 6 and holes tapped in the face plate. Adjustably attached to the central part of the dia- 65 phragm by means of a stem 11 and nuts 12 is a front electrode 9 faced with a plate 10 of carbon. The carbon plate 10 forms the front wall of a chamber 13, for containing the current carrying carbon granules, the rear wall 70 of the chamber being formed by a second carbon plate or electrode 14 mounted upon a metallic plate 15 having a screw threaded stem 16. This back electrode 14 is sunk in a depression of a large metal block 17 which 75 is centrally tapped to receive the stem 16.

Surrounding the carbon chamber and forming the side walls thereof is a large metal block 18. The blocks 17 and 18 are of 80 large mass and of good heat conducting material, such as brass or copper, in order to carry away from the granules in the carbon chamber the heat developed therein by the electric current. In order to prevent short paths for the current from one electrode 85 through the block 18 to the other electrode, circular strips or bands 19 of insulating material such as paper or mica cover those portions of the inner walls of the block 18 which lie directly adjacent to the electrodes. 90 However, the middle portion of the walls of this chamber are left bare thus insuring direct contact between the carbon granules and the mass of the heat conducting block 18. 95

Extending inwardly from the block 18 toward the central portion of the carbon chamber are a plurality of prongs or spurs 100 of metal, generally conical in shape but flattened on either side to avoid close proximity to the carbon electrodes. These prongs lying in direct contact with the hottest portion of the carbon chamber and leading directly to the large mass of metal surrounding the carbon chamber provide good heat 105 conducting paths away from the central portion of the mass of carbon within the chamber, and also to a certain extent prevent the front electrode from being overheated.

The block 17 is secured to the block 18 by 110

screws 20, 20 but insulated therefrom by bushings surrounding the screws and by a mica sheet 21.

In order to support the working parts of the transmitter in the casing a plate or bridge piece 22 is held to the face plate by flat headed screws 23, 23 and adjusting screws 24. The piece 22 embraces the block 18 and is threaded internally at 25 to engage external threads on the block. The usual mica diaphragm 27 for the front electrode is clamped to the block 18 by the screw threaded ring 28 and serves in the usual way to close the carbon chamber while permitting free vibration of the front electrode. Suitable terminals 29, one for the front electrode and the other for the back electrode are mounted upon insulating blocks 30, 30 fastened to the bridge piece 22.

20 I claim:

1. In a telephone transmitter the combination with the electrodes forming the front and rear walls of a chamber and current con-

ducting granules in said chamber, of a relatively large block of good heat conducting material surrounding said chamber and forming the side walls thereof said block having prongs extending to the interior of said chamber.

2. In a telephone transmitter the combination with the electrodes forming the front and rear walls of a chamber and current conducting granules in said chamber, of a relatively large block of good heat conducting material surrounding said chamber and forming the side walls thereof, and a plurality of heat conducting prongs generally conical in shape extending from the middle portion of said chamber to said block.

In witness whereof, I, hereunto subscribe my name this 28th day of February A. D., 1911.

FRANK R. McBERTY.
